(57) **CLAIM**

The ornamental design for a floor lamp, as shown and described.

DESCRIPTION

1. Floor lamp

1.1 : Perspective

1.2 : Perspective

1.3 : Front

1.4 : Back

1.5 : Left

1.6 : Right

1.7 : Top

1.8 : Bottom

1.9 : Enlarged

1.10 : Enlarged

1.11 : Enlarged

1.12 : Enlarged

1.13 : Enlarged

1.14 : Perspective view shown in an unfolded position

1.15 : Perspective view shown in a folded position

The parts shown by means of broken lines in the reproductions are not part of the claimed design; fig. 1.9, 1.10, 1.11, 1.12, 1.13 are the enlarged views of the portion taken at line 1.9, 1.10, 1.11, 1.12 in fig. 1.1 and line 1.13 in fig. 1.2; the

(Continued)

dash dot dash broken lines in the reproductions represent boundaries for the enlarged views and form no part of the claimed design.

1 Claim, 15 Drawing Sheets
